(57) **CLAIM**

The ornamental design for a solar cell module, as shown and described.

DESCRIPTION

1. Solar cell module

Reproduction 1.1 is a front perspective view of the solar cell module;
Reproduction 1.2 is a front view thereof;
Reproduction 1.3 is a back view thereof;
Reproduction 1.4 is a left view thereof where the right view is a mirror image;
Reproduction 1.5 is a top view thereof where the bottom view is a mirror image; and
Reproduction 1.6 is an enlarged fragmentary view of the upper right part thereof.
The dash-dash broken lines depict portions of the solar cell module that form no part of the claimed design; the dash-dot-dot broken lines define the boundary of the claimed design and form no part thereof; the dash-dot-dot-dot broken line in reproduction 1.6 depict the area of enlargement and form no part of the claimed design.

1 Claim, 6 Drawing Sheets
